Attorney

UNITED STATES PATENT OFFICE

ALBERT L. VEGORS, OF WEBSTER CITY, IOWA

PLOWSHARE

Application filed December 21, 1928. Serial No. 327,568.

This invention relates to an improved plow-share which is especially, but not necessarily, adapted for plowing sweet clover sod.

5 My principal object is to provide a plow-share having an auxiliary or extension cutting element at the heel end of the body, the cutting edge of this extension being coincident with the main cutting edge, whereby 10 to provide a structure which increases the length of the cut without increasing the draft to any appreciable extent.

Other features and advantages of the invention will become more readily apparent 15 from the following description and drawing.

In the accompanying drawing, wherein like reference characters are employed to designate like parts throughout the same:

20 Figure 1 is a perspective view of the improved plow-share attached to the conventional mold-board.

Figure 2 is a plan view of the improved plow-share per se.

25 Figure 3 is a longitudinal sectional view taken approximately upon the plane of the line 3—3 of Figure 2.

In the drawing, the reference character 4 designates the customary mold-board and 5 designates the improved plow-share which 30 is bolted or otherwise connected thereto. The body portion of the plow-share is designated by the reference character 6 and this is provided with a main cutting edge 7 and the usual point 8 at one end. At the outer or heel end is the supplemental cutting element in the form of an extension 9. This is formed integral with the body portion and has its cutting edge disposed coincident with the main cutting edge 7. This extension is 40 of a width approximately equal to one half of the complete width of the body portion and thus leaves a space 10 between itself and the mold-board. The extension here shown is comparatively short, but it is understood that it may be increased or decreased depending on the length or cutting edge desired and also depending on the thickness of the metal from which the casting is formed, the idea here being to maintain a desired degree of rigidity and to

thereby prevent easy distortion or breakage.

As before stated, the gist of the invention is in equipping the heel end of the casting with an extension of the proportions represented having its cutting edge disposed in 55 alinement or coincident with the main cutting edge in order to sever more sod without increasing the draft.

This arrangement decidedly increases the efficiency of the structure, renders it more 60 positive and dependable in performance, provides for economy in manufacture and sale, and permits the invention to better fulfill the requirements of a structure of this class, particularly adapted for cutting deep 65 matted roots, such as are found in sweet clover sod.

A careful consideration of the description in conjunction with the drawing will enable a clear understanding of the invention to be obtained. Hence, a more lengthy 70 description is regarded unnecessary.

Minor changes in shape, size and rearrangement coming within the field of invention claimed may be resorted to in actual 75 practice if desired.

I claim:

A plow-share for cutting deep matted roots in sweet clover sod comprising a single casting including a body portion having a cutting edge and a downwardly and upwardly curved portion at one end of the cutting edge, and a relatively narrow extension at the heel end of the body also having a cutting edge coincident with said first named cutting edge, said extension being of a width approximately equal to one-half the width of said body portion for providing a space between the share and the mold board when in operative position.

In testimony whereof I affix my signature.

ALBERT L. VEGORS.
